UNITED STATES PATENT OFFICE.

CORNELIUS VANDERBILT, OF NEW YORK, N. Y.

CONSTRUCTION OF BODY-BOLSTERS FOR RAILROAD-CARS.

SPECIFICATION forming part of Letters Patent No. 710,636, dated October 7, 1902.

Original application filed November 22, 1901, Serial No. 83,262. Divided and this application filed March 12, 1902. Serial No. 97,919. (No model.)

To all whom it may concern:

Be it known that I, CORNELIUS VANDERBILT, a citizen of the United States, and a resident of the city and county of New York, 5 borough of Manhattan, and State of New York, (and whose post-office address is 608 Fifth avenue, in said city,) have invented certain new and useful Improvements in the Construction of Body-Bolsters for Railroad-Cars, of which 10 the following is a specification.

My invention has relation to the construction of railroad-cars, and it has special application to cars wherein cylindrical (or other appropriately-formed) tanks are employed for 15 the transportation of oil, grain, &c.; and the special object of my invention is to improve the construction of the body-bolster which enters into and forms part of the car-frame construction. In devising the structure here- 20 inafter described I have paid special attention to its organization to the end that commercial forms of iron may be largely, if not wholly, employed and wherein the maximum carrying capacity and strength consistent 25 with a minimum amount of weight in the volume of material utilized may be had.

The embodiment of my invention herein illustrated may be advantageously employed in the improved tank-car and metallic-car construction for which I have applied for Letters 30 Patent on the 22d day of November, 1901, Serial No. 83,262, of which this case is a division; and it resides in the novel features of construction and combination of parts hereinafter described, and finally pointed out in 35 the claims.

In the drawings forming part of this specification, Figure 1 is a plan view of the body-bolster and a portion of a car-frame embodying my invention. Fig. 2 is a side elevation of the latter, partly in section, the section being taken substantially on the line $y-y$, Fig. 1. Fig. 3 is an end elevation of the body-bolster. Fig. 4 is a sectional elevation of the same, taken on the line $z-z$, Fig. 2. Fig. 5 is a perspective view of one of the bolster vertical plates or wings. Fig. 6 is a perspective view of the bolster and a part of the longitudinal sills. Fig. 7 is a like view of the bolster bed-plate. Fig. 8 is a like view of the sill-chair, enlarged. Fig. 9 is a perspective

view of a modified form of bolster, only the upper portion being shown; and Figs. 10, 11, 12, and 13, like views of further modifications.

In the drawings, 11 are the longitudinal sills of the body-framing, which, comprising I-beams having the upright webs 2 and top base-flanges 3 4, as in the application before mentioned, extend from end to end of the 60 frame, there being no sills outside (transversely) of these two.

In plan, Figs. 1 and 6, the bolster forms a lateral channel, the upper edges of which are downwardly depressed or segmentally disposed on lines concentric with the tank (if a circular one is employed) and which bolster forms a cradle, in which the tank rests and to which it may be secured.

The bolster comprises, as embodied herein, 70 three parts—the wings 5, each having their upper edges 6 formed on the segment of a circle concentric with that of the tank, when used to support a tank such as shown in the before-mentioned application, and an up- 75 wardly and outwardly extending lower edge 7, which allows clearance for the curving of the truck and the bolster side bearings; the channel-iron bed or base plate 8, having a central flat or plain section 9 and outwardly 80 and upwardly converging end pieces 10, bordered at the sides by the upwardly-extending flanges 11; the segmental T-irons or cradle-pieces 12, having a horizontal flange 13 disposed to conform to the curve of the tank 85 course and concentric therewith and the lower pendent intermediate web 14, and the compression or sill chair 15, having a lower web 90 16, side and end webs 17 and 18, and cross-webs 19, merging into an enlargement 20, hav- 95 ing an aperture 21.

Instead of using the curved angle-irons 12 to form cradles to directly or intermediately support the tank I can avail myself of the following modifications in whole or in part 95 without departing from the underlying scheme of construction.

In Fig. 9 an inverted channel-iron 22, having its cross-web 23 curved to conform to that of the tank, (or its course,) is set in between 100 the wings 5 and both parts secured together by rivets (or otherwise) passing through the

wings and the pendent curved flanges 24. This construction efficiently ties the wings 5 together and forms a cradle, in which the tank may rest.

5 In Fig. 10 the wings 5 are transversely tied together by an I-beam 25, the curved web 26 of which is horizontally disposed, the curved flanges 27 being riveted to the wings 5.

In Figs. 11, 12, curved angle-irons 28 29 are used to take the place of the T-iron 22, the curved web being adapted to receive the tank and the flange 30 being riveted to the wings 5. The curved angle-irons may be secured on the inside or outside of the wings 5, as shown in Figs. 11 and 12, respectively.

In Fig. 13 a substitute for the T-iron 22 is made by riveting two curved angle-irons 31 to the upper edge 6 of the wing 5 by their flanges 32, the horizontal webs of the angle-irons being curved.

The parts of the bolsters are assembled, and it may be united to the I-beams or sills 1 as follows: The plates 5, Fig. 10, have projections 33 extending in the same plane as the body of the plate, and from these projections extend the ears or flanges 34, provided with apertures 35, the location of the projections 34 being such as to permit them to be received within the upper and lower flanges 34 of the I-beams. Each of the plates or wings 5 are riveted at their lower edges 7 to the flanges 11 of the base-plate 8 except adjacent the intermediate section 9, the lower edge 7 of the wings 5 having the same upward inclination as said flanges. The upper curved edge 6 of the wings are secured to the pendent intermediate webs 14 of the segmental T-irons 12, the pendent web 14 being preferably located on the outside of the wings, so as to give breadth to the bearing of the tank thereon, and the said edge preventing dropping of the cradle-pieces if the rivets shear or break. The lower web 16 of the chair or casting is seated within the flanges 11 of the base-plate and rests upon the central flat portion thereof, both parts being provided with holes 36 37, permitting them to be riveted or otherwise secured together, the central portion of the bed-plate having an aperture 38, 45 alining with the aperture 21 in the chair to permit the passage of a king-bolt or other pivoting device, and to the under side of the central portion 9 of the bed-plate is secured a flat plate 39, forming the upper portion of the disk-shaped center-bearing 40, having a king-bolt aperture 41, alining with the apertures 21 38 in the bed-plate and chair.

It is clear that instead of employing the I-beam sills 1 to tie the wings 5 together laterally thereof this may be accomplished by the channel or I beams 22 25 or in any other desired way and other modifications made in my invention without departing from the spirit thereof.

I claim—

1. A bolster comprising a flanged bed-plate, plates or wings extending upwardly therefrom and secured to said flanges, and lateral extensions having upright flanges secured to the upper edges of said plates.

2. A bolster comprising a flanged bed-plate, the intermittent plates or wings extending upwardly from said flanges, the upper edges of the wings being downwardly curved, and downwardly-curved lateral enlargements secured to the curved edges of said plates or wings and extending over the space between the inner ends of the wings.

3. A bolster comprising bed or base plates, the vertical side plates secured to the base member and intermittent between their ends to form an opening therethrough, the segmental cradle-pieces secured to the upper edges of the plates and extending over the opening, combined with the longitudinal sills 85 extending through said opening and beyond the cradle-pieces, and means for securing the bolster to said sills.

4. The bolster comprising the base-plate, the vertically-disposed wings having laterally-disposed flanges, and the segmental cradle-pieces secured to the wings.

5. A bolster comprising the base-plate, having the central flat portion and upwardly-inclined extensions therefrom, the vertical 95 plates secured to the sides of the base-plate, and the segmental cradle-pieces so secured to the upper edges of the vertical plates or wings.

6. The bolster comprising a base-plate, having a central flat portion and outwardly and upwardly inclined ends, vertical plates or wings secured to said inclined ends, and the segmental cradle-pieces secured to the upper edges of said wings.

7. A bolster comprising a base-plate, the 105 compression-chair, secured centrally thereto, the vertical plates or wings secured to the plates and the segmental cradle-pieces secured to the upper edges of said wings.

8. A bolster comprising a base-plate having 110 flanges vertical plates or wings secured to the said flanges and the segmental cradle-pieces having a depending web secured to the upper edges of said wings.

9. A bolster comprising a flanged base-plate, the vertical wings secured exteriorly to said flanges, and cradle-pieces each having a segmental horizontal web, and a segmental vertical web secured to the side of the vertical wings, the upper edges of said wings lying 120 within the plane of the horizontal web.

Signed at the city and county of New York this 3d day of March, 1902.

CORNELIUS VANDERBILT.
